FOREIGN PATENT DOCUMENTS

GB 6240960 * 11/2022

Primary Examiner — Paula Allen Greene

(74) Attorney, Agent, or Firm — David W. Carstens;
Carstens, Allen & Gourley LLP(57) **CLAIM**

The ornamental design for a sports ball urn as shown and described.

DESCRIPTION

FIG. 1 is a front perspective view of a sports ball urn of the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed broken lines depict portions of the sports ball urn that form no part of the claimed design.

1 Claim, 7 Drawing Sheets(56)
